UNITED STATES PATENT OFFICE

HENRY MILLER PATTERSON, OF RICHMOND, VIRGINIA

COOKING APPARATUS

Application filed June 7, 1930. Serial No. 459,729.

This invention relates to improvements in cooking apparatus; and more particularly to the type of range adapted to burn wood or coal, although other types of fuel may be used without departing from the invention.

The prime object is to so arrange the various units making up the stove as to utilize maximum heating efficiency, and at the same time, secure the amount of heat required for the various units in the natural course of circulation, so that the unit requiring the most heat will be closest to the source of heat, and those requiring less heat will be remote, not only from the source of heat, but from the cycle of circulation, bearing in mind the phenomenon that warmed air rises.

Heretofore ranges having broilers, baking ovens and warmers, have either required a plurality of heating units to heat the various units or have so arranged the various units to be heated as to obtain a very sluggish and inefficient cycle of circulation.

Another object is to provide means for concentrating on certain of the units to be heated, whereby the other units will be cut out of the cycle of circulation.

Still another object is to utilize a single source of heat for heating a plurality of units, the unit being so arranged that the warm air is never forced downwardly until the end of the cycle is completed.

Other objects will be disclosed in the specification and claims forming part of this application.

35 In the drawings:

Figure 1 is a perspective of the range;

Figure 2 is a section taken on line 2—2 of Figure 3;

Figure 3 is a section taken on line 3—3 of Figure 2;

Figure 4 is a section taken on line 4—4 of Figure 2;

Figure 5 is a horizontal section taken on line 5—5 of Figure 2; and

45 Figure 6 is a fragmentary rear elevation of the upper portion of the stove with parts broken away.

Referring to the drawings:

50 Numeral 7 designates a range of the coal or wood type having a fire box 8 mounted in

one end of said range 7. Immediately adjacent, and on the same level with the fire box 8, is a broiling oven 9. Above the fire box 8 and broiler 9, is the cooking surface 10 of the range 7, in which is formed openings 55 11 in which are set lids 12. Between the cooking surface 10 and the fire box 8 and broiling oven 9 is formed a passage 13.

A baffle plate 14 is positioned in the passage 13 extending lengthwise of said passage, said 60 baffle being composed of upper and lower plates 15 and 16, respectively, with insulating material 16, such as asbestos, between the plates 15 and 16. The baffle plate 14 thus divides the passage 13 forming an upper passage 18 and a lower passage 19. In front of

the upper and lower passages 18 and 19 and between said passages and the fire box 8, are positioned dampers 20 and 21 to control the 65 passage of heat from the fire box 8 through the respective passages 18 and 19. Within the broiling oven 9 are removable trays 22 of the usual construction. Immediately adjacent 70 the broiling oven 9 is located a warming oven of substantially the same height as the broiling oven, the top surface 24 of the warming oven 23 being a continuation of the top surface 25 of the broiling oven 9. Immediately 75 above the warming oven 23 and to one side of said broiling oven 9 is formed a baking oven 26. A passage 27, which is a continuation 80 of the passage 13, is formed between the warming oven 23 and the baking oven 26 and extends around the side 28 and over the top 85 29, and down the opposite side 30, where it strikes a baffle 31 and is directed by said baffle out through a flue 32. Below the baffle 31 the passage 27 continues to join the passage 13. Where the passage 13 emerges from between the cooking surface 10 and the broiling oven 9, a damper 33 is positioned so as to 90 connect the passage 13 direct with the flue 32, or upon being rotated, to cut off a passage 34 leading directly to the flue 32 and to connect 95 directly with the passage 27.

The damper 33 has a short heavy portion 35, which, when rotated, will close the passage 34 and a long slender blade 36 which serves to close the passage 27 when rotated to that position. The heavy portion 35 serves 100

as a counterweight and facilitates the operation.

5 A warming shelf 37 is mounted directly above the cooking surface 10, and has on its under side immediately adjacent the back 38 of the range 7, a plurality of openings 39 in the form of a grille 40. A damper 41 is mounted in the flue 32 so as to control the draft. This damper is of the usual construction.

10 As actually operated, due to the fact that the broiling oven is adjacent the fire box, and the side wall of the broiler forms the side wall of the fire box, heat from the fire box will be transmitted directly to the broiler through the common side wall. This gives very intense heat at the top of the broiler which is the ideal place for the heat to originate, as most broiling is done from the top. In addition, if it is desired to utilize the broiler, the damper 20 may be turned to shut off the passage 18, and the damper 21 turned to open the passage 19 so that the heat from the fire box will flow directly over the top of the broiler. In case it is desired to concentrate the heat against the upper cooking surface, the damper 21 will be turned to close the passage 19, and the damper 20 opened to allow the heat to pass through the passage 18, thus 25 bringing the heat directly in contact with the cooking surface.

30 In case both the broiler and the cooking surface is desired to be utilized, dampers 20 and 21 may both be turned to open position which will divide the heat due to the baffle plate 14. When first starting the fire it may be desirable to obtain the maximum draft in which case the damper 33 will be turned to close the passage 27 and direct the heat up 35 the passage 34 which leads directly to the flue. When the fire has reached the required heating state, and it is desired to utilize the warming oven and baking oven, the damper 35 is turned to close the passage 34 and allow 40 the heat to pass from the passage 13 directly into the passage 27 over the top of the warming oven 23 around the side of the baking oven 26 and over the top 29 and down the opposite side 30 to the baffle 31, from where 45 it is directed to the flue 32. This cycle of operation, of course, necessitates one or both of the dampers 20 and 21 being operated.

50 The fumes from the cooking vessels on the cooking surface 10 will ascend and be drawn through the grille 40 into the flue 32. This prevents the cooking odors passing out into the room, and at the same time, serves to heat the warming shelf 37 and carry off surplus heat.

55 60 It is obvious from my description that I have allocated the various units in such a manner as to benefit in the most efficient manner from the natural circulation of the heat in respect to the duties to be performed by the respective units. For instance, it is gen-

erally recognized that a broiler requires a very hot fire, preferably from the top. A warming oven naturally only requires a small amount of heat, and a baking oven requires a very evenly distributed heat, preferably from the top and bottom. In my oven, not only does the heat distribute from the top and bottom, but along the sides, making an evenly diffused heat admirably adapted to baking. By placing the broiler immediately adjacent the fire box, extreme heat is obtained, and by passing the heat along the adjacent side and over the top of the broiler, the source of heat in the broiler will be from the top. In the case of the warming oven, the heat passes over the top and only a very small quantity will descend as the warming oven too is insulated. By placing the baking oven above the source of heat, the heat will rise and encircle the oven, being aided by the draft formed in the flue which will overcome the hesitancy of the heat to descend on the baffle said of the oven. It is likewise apparent that I can close off the various units when they are not in use, thereby increasing the efficiency of the other units.

65 It is equally obvious that the principle of this range can be utilized in all types of stoves and is not limited to a coal stove range.

70 What I claim is:

A cooking apparatus comprising a source of heat, a broiling oven adjacent said source of heat, a warming oven adjacent said broiler, a baking oven above said source of heat, the cooking surface and broiler forming a passage leading from the source of heat and continuing over the warming oven, said baking oven having at its far side a passage leading upward and merging with said passage over the warming oven, and continuing over the top of the oven down the side nearest the heat source, a baffle in said passage, said passage continuing under the baffle to a flue at the rear of the cooking apparatus, a damper positioned between the warming oven and broiler and adapted to close the passage passing over the broiler and warming oven, and upon rotation adapted to open this passage and close the passage extending down the near side.

75 80 85 90 95 100 105 110 115 120 125 130 In testimony whereof I affix my signature.

HENRY MILLER PATTERSON.
